(57) **CLAIM**

The ornamental design for a fence hanger, as shown and described.

DESCRIPTION

FIG. 1 is a top perspective view of a fence hanger showing our new design thereof;

FIG. 2 is a side view of the fence hanger shown in FIG. 1; and,

FIG. 3 is side view of the fence hanger, with environmental structures, shown in FIG. 1.

Elements shown in broken lines show environmental structures of the fence hanger and form no part of our design.

1 Claim, 2 Drawing Sheets**FIG. 1**

FIG. 2

FIG. 3
